UNITED STATES PATENT OFFICE.

THOMAS W. SWENEY, OF READING, PENNSYLVANIA.

DESIGN FOR A BADGE.

Specification forming part of Design No. 5,835, dated April 30, 1872.

To all whom it may concern:

Be it known that I, THOS. W. SWENEY, of Reading, county of Berks, State of Pennsylvania, have invented a Design for a Badge, or mark of distinction for a society, of which the following is the specification:

The figures in the accompanying drawing fully illustrate my design, which consists mainly of a pentagon, within which are six fields.

Like figures indicate like parts in each figure.

Figure A is represented with all the fields occupied. Fig. B is identical with Fig. A, with field 6 left blank. Fig. C is identical with Fig. A, with fields 6 and 4 left blank, and field 5 to be occupied, as hereinafter described. Fig. D is identical with Fig. C, with the fields 1, 2, 3, 4, and 6 left blank. Fig. E is the same as the former figures, with all six fields blank.

Figure A is represented as follows: In field 1 is a representation of an open book. In field 2 is a representation of a spear and shield. In field 3 is a representation of a sword. In field

4 is a representation of a skull and cross-bones. In field 5, at or about the center, is the letter S, encircled by the letters, in rotation, as follows: J. F., I. F., T. L., T. H., B. M. In field 6 is an eye encircled with radiating rays.

In field 5 of Figs. C and D is a representation of a castle. Fig. D represents the reverse of Figs. A and B. Fig. E represents the reverse of Fig. C.

The Figs. A, B, C, D, and E each represents a degree; and all the several degrees of a society.

What I claim as my invention, and desire to secure by Letters Patent, is—

The design represented by the Figs. A, B, C, D, and E, any or all of them, made substantially as hereinbefore described, and to be used as badges or marks of distinction, for the purposes set forth.

THOS. W. SWENEY.

Witnesses:

JOHN O. MATTHEWS,
SAMUEL J. FAIR.
